US0D1076281S

(12) **United States Design Patent** (10) **Patent No.:** **US D1,076,281 S**
Chen (45) **Date of Patent:** **** May 20, 2025**

(54) **LITTER BOX**

(71) Applicant: **Ningbo Mingtan Technology Co., Ltd,**
Yuyao (CN)

(72) Inventor: **Zhanli Chen**, Yuyao (CN)

(73) Assignee: **Ningbo Mingtan Technology Co., Ltd,**
Yuyao (CN)

(**) Term: **15 Years**

(21) Appl. No.: **29/975,440**

(22) Filed: **Nov. 27, 2024**

(51) **LOC (15) Cl.** **30-11**

(52) **U.S. Cl.**
USPC **D30/161**

(58) **Field of Classification Search**

USPC D30/161, 162, 199, 108, 171, 119, 118
CPC A01K 1/0107; A01K 1/011; A01K 1/0114;
A01K 1/0121

(57) **CLAIM**

The ornamental design for the litter box as shown and described.

DESCRIPTION

FIG. 1 is a front, right, and top perspective view of the litter box, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the litter box that form no part of the claimed design.

1 Claim, 8 Drawing Sheets
